ABSTRACT OF THE DISCLOSURE

In the printing method in which electrically charged particles are launched from an electrode and pass through a stencil and onto a target surface, free charges flow sporadically from the launching electrode to the stencil. The resultant disruption in the uniform intensity of the printing field between stencil and target surface interferes with particle trajectories and printing definition. This invention limits variation in printing field intensity from this cause by accumulating away from the field, stencil charges deposited which tend to disrupt uniform field intensity during printing.

REFERENCE TO COPENDING APPLICATIONS

This application is a continuation-in-part of our copending application Ser. No. 767,018 filed Aug. 26, 1968, which is a continuation-in-part of application Ser. No. 651,946 filed July 7, 1967, which is in turn a continuation of Ser. No. 479,461, filed Aug. 13, 1965.

BACKGROUND OF THE INVENTION

Field of the invention

This invention relates to improved methods and apparatus for printing, decorating or to like purposes depositing printing particles such as fine electrostatic pigments by electrostatic means on surfaces of planar or curvilinear configuration, and is applicable to the direct labeling or decoration of sheet or containers and other objects of irregular or intricate shape made from paper, plastic, glass, metal or combinations of these, or of other materials which have conductive or nonconductive surfaces. More particularly, the invention is concerned with achieving more faithful replication of characters, logos and like patterns of printed image by limiting free charge accumulation at the image-defining stencil, to stabilize the stencil charge condition at desired levels for heightened fidelity of image to the stencil apertures.

Electrostatic toner particles, either solid or liquid, may be printed on a target surface by passage of the massed particles through a stencil which is positioned opposite and in closely spaced relation to the target surface. An electrical field is maintained between the target and a spaced voltage source within which field the stencil is positioned so that electrically charged printing particles within the field are induced to move through stencil aperture areas corresponding to the pictorial or literal matter to be printed, and to project onto the target surface.

Creation of the required electrical field is effected by the application of a voltage differential between a launching electrode and a counter-electrode. A stencil is placed between the electrodes as is the target surface for printing, so that stencil passing particles are caused to deposit on the surface. Counter-electrode means may have any of various particular forms, such as the target sur-

face itself where conductive, or a conductive backing for a non-conductive surface or a separate electrode, in effect backing the target surface. In container printing, a counter-electrode inserted in the container, or projected only partially thereinto so as to ionize fluid within the container, creates an effective counter-electrode condition.

Prior art

A continuing problem in electrostatic printing, attributable at least in part to sporadic free charge flow to the stencil, is the difficulty of achieving perfect replication of the stencil aperture. Often the lettering is "out of square," having attenuated corners and concave intermediate portions, with an unfortunate randomness that causes a picturesque illegibility in the final print, particularly where lettering is extensive and relatively small as, for example, use instructions on a package.

In U.S. Pat. 3,364,853 issued to us on Jan. 23, 1968, we proposed a method and apparatus for preventing free charge flow to the stencil. The present invention is useful where it is not possible or convenient to control flow before it deposits on the stencil.

SUMMARY OF THE INVENTION

The present invention is predicated on the major concept, among others, of stabilizing the stencil charge condition or potential relative to the target surface charge condition, and more particularly accumulating free charge flow to the stencil during and between successive printing particle launchings, away from the stencil. It has been found that at the high field strengths typically employed in electrostatic printing for rapidity of particle movement, significant, if variable, amounts of free charge, resulting from movement from the electrode of loosely bound charges not associated with the printing particles, cascade from the launching electrode, traverse the gap between stencil and electrode and alter the charge condition of both stencil and object, the former more than the latter, so that the stencil charge alteration varies the relative potentials of stencil and object. Potential relationship is determinative of fidelity in printing to stencil openings. Nonuniform printing results, increasingly with time. Prevention of random charge increases on the stencil will limit variations in field intensity and accordingly produce more uniform and faithful printing. This prevention can be accomplished by accumulating the charges away from the field.

In particular, the invention provides a method of printing upon the surface of an object that includes depositing electrically charged particles onto the surface through a spaced stencil and through an electrostatic printing field maintained between the object surface and the stencil in a manner permitting random free charge flows tending to alter in time the printing field intensity, and accumulating such charge from the stencil away from the printing field to thereby limit field intensity variation. In practice, the charge accumulation is carried out to maintain the charge condition of the stencil relative to the object surface at a constant value i.e., which does not deflect particles passing therethrough and through the field beyond from their trajectory more than is desired for final print appearance.

Charge accumulation is accomplished by a capacitance electrically connected to the stencil and away from the field, which capacitance acts to accumulate charge during charge flow to the stencil as needed to maintain uniform printing field intensity. A resistance may be provided in the capacitance circuit to control the charge level of the stencil relative to the object. In particular embodiments, the stencil may be positioned within a field extending from the object surface to a voltage source spaced from the stencil. Printing particles intended to be deposited may

be introduced preferably precharged into the field at the voltage source side of the stencil. The method of the present invention is particularly well suited to rapid, sequential printing of containers by passing electrically charged particles through the stencil and a uniform field between the stencil and object.

Apparatus is provided for carrying out the above method of printing on the surface of an object that includes means for forming an electrical field including a voltage supply and stencil means within the field for selectively passing electrically charged particles to the surface, the voltage supply including an electrode having a charge condition tending to randomly subject the stencil to charge flows disruptive of the potential relationship between the stencil and the object and means limiting accumulation of charge on the stencil, such as a capacitor electrically connected to the stencil. A resistor in series or parallel with the capacitor may be provided for control of charge levels on the stencil. In installation for the printing of containers, for which the invention is particularly adapted, means are provided defining a container printing station within the printing field, said container providing the object surface to be printed.

BRIEF DESCRIPTION OF THE DRAWINGS

FIG. 1 is a schematic view of one embodiment of the apparatus of the present invention;

FIGS. 2 and 3 are illustrations of printing characteristics that vary with field intensity; and

FIG. 4 is a graph of stencil and object voltage conditions with time.

DESCRIPTION OF THE PREFERRED EMBODIMENTS

Referring, now, to the drawings in detail there is shown in FIG. 1 a typical improved printing apparatus according to the present invention, particularly adapted to print or decorate an open-mouth container 10 having a printable surface 10a. Printing means for depositing electrically charged particles upon the container surface are shown including a printing particle supply comprising a hopper 12 having a charging wire 14 connected to, e.g., a positive D.C. source (not shown) for charging printing particles 16, conveyor belt 18, suitably of rubber, cloth or mohair, and driven continuously beneath the hopper outlet between sheaves 19. Printing particles 16, electrically charged within the hopper, fall by gravity onto the belt 18 and are carried to the launching area. There, a launching electrode in the form of rotating cylinder 22 is provided connected at 24 to, illustratively, the positive terminal 26 of a D.C. voltage supply 28 so that the particles 16 are repelled by the electrode 22 and are thus launched as a stream 20. A counter-electrode means is provided to define an electrical field with electrode 22 including conductive probe 32 positioned within container 10 at the open mouth or neck thereof. The probe is connected at 34 to, illustratively, the negative terminal 38 of the D.C. voltage supply 28, so that the particles of stream 20 are attracted to the counter-electrode and surface 10a. Within the field thus defined there is placed a printing pattern defining stencil 40 of dielectric material or preferably, conductive material, generally of brass or beryllium-copper shim stock, which is typically biased to a desired charge value by connection to potentiometer 44.

The stencil 40 is provided with image defining apertures 40a which permit portions of printing particle stream 20 to pass the stencil and impinge on the container surface. The stencil apertures may be produced mechanically as by blanking out with a suitable die or in a punch press, or chemically or electrochemically, by etching away unmasked areas of the sheet stock, or by other suitable means.

In the typical arrangement shown in FIG. 1, the electrical field will generally have a quite high potential, e.g., on the order of 20,000 to 100,000 volts or more. This is provided by application of a voltage differential

to the electrodes in a known manner and ordinarily by application of 40,000 to 60,000 volts to the launching electrode and 10,000 to 20,000 volts of opposite polarity to the probe of the counter-electrode.

For illustrative purposes herein, the launcher will be considered as positively charged and the probe therefore negatively charged. The particles will then be positively charged. It is to be noted that it is the relationship of polarities of the electrodes to one another and to the particles and their absolute value that is of significance in printing, not their sign. So, while the illustrative apparatus is described herein with a positively charged launching electrode and a negatively charged counter-electrode and employing positively charged particles, all signs may be opposite.

Under the strong field conditions just described, there occurs a phenomenon known as free charge flow from the launching electrode to the stencil, as a result of the high field strength at the launcher driving off charge not associated with the particles. This flow has been found to have an irregular pulsing character, i.e. to be random or sporadic. Unless accumulated, as provided for in the present invention, the charge flows to the stencil, even in the absence of electrical connection therebetween and independently of particle flow. The presence of these charges on the stencil alters the stencil charge condition which has been selected to be at a particular value relative to the object prior to commencing operations and which is desirably stabilized at the selected relative level, thus to insure uniform or constant field intensity during printing. The potential between stencil and object is thus altered and printing field changed. Moreover these charges may tend to move to the aperture perimeters and there produce local charge concentrations which may significantly affect direction of particle movement beyond the stencil to the object. While it is contemplated that the stencil 40 during printing may have any desired closeness of approach to the container surface 10a, generally it is desirable to maintain at 36 sufficient spacing to preclude contact smearing of the deposited particles. The spacing at 45 between the launching electrode and stencil, however, is relatively wide, typically in the range of 3 to 15 centimeters, to promote and insure dispersion of particles constituting the stream 20 for free passage through the stencil openings.

Generally, the stencil charge condition is initially set at a value such that the ratio E_a/E_t is maintained between about 0.6 and about 3.0 where

$$E_a = (V_3 - V_2)/L_a$$

$$E_t = (V_1 - V_2)/L_t$$

V_1 being the voltage of the launching electrode 22, V_2 the voltage of the counter-electrode or counter-conductive means 32, V_3 the voltage of the stencil 40, L_t is the distance (in centimeters) between the launching and counter-electrode means, and L_a is the distance between the stencil openings and counter-conductive means. Where the printing target surface serves as the counter-electrode, or has a voltage corresponding substantially to that of an associated counter-electrode, then in the above equations V_2 may be considered to be the voltage at that surface, and L_t and L_a are measured in relation to the surface. When the counter-electrode does not conform to the target surface voltage, the field voltage at the surface is determined and used for V_2I_a , being the distance between the stencil apertures and the target surface.

Typically use is made of a launching field strength of about 6,000 v./cm. to about 20,000 v./cm. Essentially the same image may be presented when both the launching field strength (E_t) and air gap field strength (E_a) are increased by the same factor to maintain a constant ratio E_a/E_t . Factors in the selection of field strength are the configuration of the object to be printed, the spacing between the launcher and object and the printing particle

characteristics. It has been found that image of good clarity may be produced using an air gap spacing L_a less than about $\frac{1}{4}$ inch. However, it is preferable to keep this spacing at around 0.07 inch or less when printing fine detail. Generally, the closer the stencil openings are to the target surface, the more sharply defined the image.

When the ratio E_a/E_t is too low, as, in an illustrative situation, substantially below 1.0, the resulting image of a large block letter may tend to be distorted with bulging sides, indistinct edge definition, acute inside corners and rounded outside corners, on the other hand, an increase in the E_a/E_t ratio to greater than about 1.8 may produce a narrowing effect with sharply pointed corners as in FIG. 3. With the ratio maintained between about 1.0 and 1.8 the image is of good definition in keeping with FIG. 2. The potentiometer 44 provides a variable control to maintain the desired E_a/E_t ratio, generally by maintaining the charge on the stencil at a level closely approximating the local field strength.

Obviously, in view of the foregoing ratio analysis, the image fidelity factor is influenced by the stencil charge condition. Variations from the preset level, i.e. increases, due to relatively great free charge flows onto the stencil relative to the object can change the printed images in the manner illustrated in comparing FIGS. 2 and 3. This invention is concerned with accumulating free charges flowing to the stencil away from the stencil thereby to stabilize the printing field between stencil and object at a predetermined constant level.

Referring again to FIG. 1, the surface 22a of the electrode 22 receives by gravity feed the charged particles 16 from the belt 18 and conveys them angularly to opposite the stencil 40 and thus into the electrical field between electrodes 22 and 32. Once in the field, the particles, which it will be remembered are charged to the same sign as the electrode 22, are repelled. Assuming a launching level field, as above described, the particles so leave the surface of launcher 22 and are electrically attracted to the target surface 10a. Independent of particle flow, free charges on the launching electrode 22 will leave the electrode and travel toward an adjacent attracting potential e.g. the counter-electrode or the stencil between the electrodes. It has been found that such free charge flow occurs continually, although not at constant levels. It is with the minimizing of the deleterious effect of surges of free charge flow that the present invention is concerned. With reference to FIG. 4 the effects of free charge flow in an apparatus like that depicted in FIG. 1 is shown graphically. The voltage (charge condition) of the printable surface and that of the stencil both increase with time. This is shown by a comparison of lines A (object voltage or charge condition) and B (stencil voltage or charge condition). This increase is attributable to the continuing flow of free charge from the launching electrode 22. The difference between lines A and B represents the voltage difference between stencil 40 and object surface 10a, i.e. the printing field intensity. It will be noted that lines A and B are parallel and that the field intensity is uniform during the time period shown in FIG. 4. With such a uniform field condition printing results are sharp because of the absence of dis-focusing effects of field intensity variation. The potential of the stencil 40 tends to increase, however, beyond the increase in potential of the object surface 10a if the free charges remain on the stencil.

Such free charges remaining on the stencil are sufficiently proximate the printing field between stencil 40 and object surface 10a to affect that field. If this field is too high in intensity the printed images are attenuated (FIG. 3), if too low the images are bloated in appearance. If the field fluctuates during printing, due for example to a variation in the stencil potential a combination of image effects results, generally giving a fuzzy appearance. In FIG. 4 the rise in stencil voltage from free charge thereon is shown on dotted line C. It will be seen

that the field intensity between the stencil and object changes continually with time. Uniform field intensity conditions of the proper value i.e. appropriate relative potentials of object and stencil (see discussion above) produce perfectly formed letters like that shown in FIG. 2.

From the foregoing it is apparent that for successful printing free charge flow surges must be prevented from altering the field intensity and that therefore charge must be prevented from accumulating on the stencil. This invention provides for accumulation of the free charges away from the stencil, and thus the field, by accumulating these charges, i.e. absorbing them, in an electrical sense, in a capacitor.

In FIG. 1, the stencil 40 is shown electrically connected through line 46a to capacitor 46 which is connected to potentiometer 44 at point of neutral voltage. By this arrangement surges in the voltage level of the stencil 40 from free charge cascades by the launching electrode 22 are withdrawn from the stencil and stored in the capacitor 46. The relative value of the stencil potential, to the object, initially is controlled by the applied potential of the potentiometer. The resistor 50 may be combined with the capacitor 46 in either parallel or series, preferably the former as shown, with both elements performing their respective functions, the resistor determining the voltage drop and the capacitor limiting sharp changes in stencil potential from flow of charge to the stencil.

Example 1.—Electrostatic printing was effected on a polyethylene container with accumulation of free charge flow by use of an apparatus similar to that shown in FIG. 1 using Sun Chemical Electroscopic Ink #CR 5559-40 having an average particle size of about eight microns. The launching electrode was charged to 40,000 volts positive and the probe counter-electrode to 8,000 volts negative. The stencil was connected to the potentiometer 28 through a 0.16 microfarad capacitor. No resistor was used. There was free charge flow from the launching electrode. A uniform field was maintained between the stencil and the container surface throughout printing and literal information was sharply defined and undistorted.

Example 2.—The apparatus of Example 1 was altered by substituting a 0.10 microfarad capacitor for the 0.16 capacitor used there. Printing was effected. Results were equivalent.

Examples 3 and 4.—Example 1 was duplicated with a resistor connected in parallel with the capacitor. In Example 3 a 100 megohm resistor was used. In Example 4 a 130 megohm resistor was used. In both instances sharply defined and faithful reproduction of stencil openings was achieved on the bottle surface, through maintenance of a uniform printing field.

As the printing particle material, a uniformly fine powder is preferred. A suitable toner powder has a particle size of about 5 to 10 microns. A low temperature melting resinous powder may be used, if it is desired to fix the toner particles by heat, desirably not so low that the particles sinter in storage. A satisfactory power is essentially composed of a non-tacky, low melting and suitably colored natural or synthetic resinous material. The composition of the toner resin does not appear to be critical insofar as electroscopic launching ability and image formation are concerned. A number of suitable electroscopic resins are described in U.S. Pat. No. 3,079,342. It is also possible in the instant invention, to use an electroconductive powder consisting of flaked and polished aluminum powder having a particle size of less than about 40 microns in diameter. The aluminum powder readily produces an image under the same conditions as employed with resin-based pigment particles, the resulting image, however, must be subsequently fixed to the surface as by application of a clear coating material. A fine dispersion of a liquid toner can be used in lieu of the pigment powder herein, it will be understood to include not only materials that may be pigments or dyes themselves,

but also resins and other materials to which pigments or dyes are added or which are otherwise given color including white and black. Techniques for fixing or otherwise subsequently treating the printed images are well known in the art.

To summarize the operation of the invention, printing particles 16 are electrically charged, are launched in a stream 20 by a like-charged launching electrode 22 and pass through stencil 40 and impinge on selected areas of a target such as container 10 behind which a counter-electrode condition is maintained by a charge on probe 32. The free charge flow normally incident to the highly charged condition of the launching electrode is accumulated after reaching the stencil 40 by provision of a capacitor 46, optionally in combination with a resistor 50 to accumulate cascades of free charge flow away from the field between stencil 40 and counter-electrode 32. With free charge accumulation thus controlled, the stencil charge condition, typically biased by adjustment of potentiometer 44 to approximate the local field strength, is stabilized despite free charges flowing from the launching electrode which, unless accumulated would remain on the stencil to upset its charge condition and disrupt printing field uniform intensity. In this event, erratic field strengths variably alter the trajectory of particles passing the stencil and cause oddly formed images. By accumulation of free charge flow in accordance with this invention printing uniformity is enhanced.

We claim:

1. The method of printing upon the surface of an object that includes launching electrically charged particles from an electrode toward said surface and through an image defining stencil therebetween and through an electrostatic printing field maintained between said surface and said stencil in a manner subjecting the stencil and object simultaneously to different increases in charge thereby tending to change the printing field intensity in time, and passing charge from the stencil to proportion increases in the stencil potential relative to increases in the object surface potential to substantially eliminate variations in the intensity of the printing field.

2. Method according to claim 1 including accumulating charge from the stencil in a capacitance electrically connected to said stencil to control charge accumulation on the stencil.

3. Method according to claim 2 including biasing the stencil to a predetermined potential.

4. Method according to claim 2 including also main-

taining a second field between said object surface and the launching electrode and introducing said particles into said second field at the launching electrode side of said stencil.

5. Method according to claim 1 including limiting the increase in potential of the stencil to the increase in object surface potential during printing to maintain constant the field intensity therebetween.

10 6. Method according to claim 1 in which said object is a container and including also positioning said container at a printing station and passing said electrically charged particles through said stencil onto said container surface.

7. Method according to claim 6 including providing a capacitance electrically connected to said stencil to control charge accumulation on the stencil.

15 8. Apparatus for printing upon the surface of an object that includes means for forming an electrical field including a voltage supply, and stencil means within said field for selectively passing electrically charged particles to said surface, said voltage supply including an electrode subjecting the stencil and the object surface simultaneously to different increases in charge thereby tending to alter the potential relationship between the stencil and the object surface over time and means collecting charge 20 from said stencil including a capacitor electrically connected to the stencil to substantially eliminate variations in the potential between the stencil and said object.

9. Apparatus according to claim 8 including also a resistor biasing said stencil.

30 10. Apparatus according to claim 9 in which said resistor and capacitor are connected in parallel.

11. Apparatus according to claim 8 for printing a container including also means defining a container printing station within said electrical field, said container defining 35 said object surface.

12. Apparatus according to claim 11 including also a counter-electrode inserted within said container.
